(57) **CLAIM**

The ornamental design for a dispenser housing, as shown and described.

DESCRIPTION

FIG. 1 is an isometric view of a top, front, and right side of an ornamental design for a dispenser housing;

FIG. 2 is a front elevational view of the housing of FIG. 1;
FIG. 3 is a rear elevational view of the housing of FIG. 1;
FIG. 4 is a right side elevational view of the housing of FIG. 1;

FIG. 5 is a left side elevational view of the housing of FIG. 1;
FIG. 6 is a top plan view of the housing of FIG. 1;
FIG. 7 is a bottom plan view of the housing of FIG. 1;
FIG. 8 is an isometric view of a top, front, and right side of another ornamental design for a dispenser housing;
FIG. 9 is a front elevational view of the housing of FIG. 8;
FIG. 10 is a rear elevational view of the housing of FIG. 8;
FIG. 11 is a right side elevational view of the housing of FIG. 8;

FIG. 12 is a left side elevational view of the housing of FIG. 8;

FIG. 13 is a top plan view of the housing of FIG. 8; and,
FIG. 14 is a bottom plan view of the housing of FIG. 8.

The evenly weighted broken lines in the Figures are for the purpose of illustrating environmental structure and form no part of the claimed design. The solid patterns shown in FIGS. 15-27 and 70-82 illustrate a series of apertures, recessed portions, and/or surface treatments provided on a dispenser housing. The solid patterns shown in FIGS. 55 and 110 illustrate some type of an arrangement of an aperture and a recessed portion on a dispenser housing.
